UNITED STATES PATENT OFFICE.

JAMES C. STANLEY, OF NEW HARTFORD, CONNECTICUT.

SPINDLE AND BEARING THEREFOR.

SPECIFICATION forming part of Letters Patent No. 247,522, dated September 27, 1881.

Application filed November 17, 1879.

To all whom it may concern:

Be it known that I, JAMES C. STANLEY, of New Hartford, in the county of Litchfield and State of Connecticut, have invented certain 5 new and useful Improvements in Spindles and Bearings Therefor, of which the following is a specification.

My invention relates to spindles and bearings therefor, and particularly to that class of 10 bearings in which both the step and bolster are connected with a reservoir from which oil is supplied.

The object of my invention is to provide 15 means whereby a spindle shall be regularly and continuously supplied with oil without at any time having much more delivered to it than is required for perfect lubrication. I attain this object by the mechanism illustrated in the accompanying drawings, in which—

20 Figure 1 is an elevation, partly in section, of a reservoir-spindle and adjacent parts of my improved construction. Fig. 2 is a modification of the sleeve shown in Fig. 1. Fig. 3 is a sectional view, with the spindle removed, of 25 the sleeve and case seen in Fig. 1.

25 A is the spindle, having the whirl B, which has upon its lower edge the flange b, which has upon its outer edge the downward-projecting lip, c. c² is a lip attached to the whirl 30 nearer the axis of the spindle, thus forming an inverted annular cup, d, whose edges overlap the lip e, which extends upward from the case D. This case has formed upon its top by the lip e the cup e', annular in form, the inner rim 35 of which is formed, when the parts are in position, by the bolster-sleeve d³, which extends above the case D, the outer rim by the lip e, and the bottom by the top end of the case and the top of the flange on the bolster-sleeve. 40 This cup receives all the oil overflowing the bolster-bearing, as hereinafter described, and prevents waste.

45 H is a sleeve, comprising the bolster and the step, h being the bolster or part of the sleeve upon which the spindle bears near the whirl, beginning at the point marked x and extending upward, and l being the step in which the lower bearing of the spindle moves.

50 The sleeve H and case D are so formed that between them will be an oil-chamber, n, which is filled with any suitable fibrous material, to filter the oil permitted to enter it or to limit

the capacity of the inducts, hereinafter described. Around the upper end of the sleeve is formed a flange, j, to retain it concentric 55 with the case D in an aperture in which it is placed, which aperture is for the greater part of the depth of the case made of considerable greater diameter than the sleeve, and at its extreme lower end only of such diameter as will permit of the introduction of the sleeve. There will, therefore, when the sleeve is inserted in the case, be formed an annular chamber, n, extending from the bottom of the flange j to the point where the larger aperture terminates, 60 the bottom of the chamber being the internally-projecting flange or collar j' on the case, which comes into contact with the sleeve. The case may, however, be bored through the diameter of the chamber and the sleeve formed with 65 flanges on both ends, as shown in Fig. 2, if it be so desired.

70 In the flanges or collars j j' are formed ducts d⁴, through which the oil enters the chamber n, it being forced in through the bottom duct 75 by the gravity of the oil in the reservoir and through the top one by its own gravity from the cup e'. Through the sleeve H are formed inducts of such capacity that the oil cannot pass through them in much greater quantity 80 than is required for perfect lubrication, and also of such capacity that any such slight excess of oil which may so pass to the spindle will be much less than its capacity to carry it out over the top of the bolster by capillary and 85 centrifugal force. These inducts may have their capacity limited by having their diameter made very small, as shown by the induct m in Fig. 2, or by having their orifices covered with some material which retards the entrance 90 of the oil, as shown at m in Fig. 1. Besides these inducts, additional ones, m², placed near the bottom of the upper bearing of the spindle and above the surface of the oil in the chamber n, may be made, to which ducts the oil is conveyed by the capillary attraction of the fibrous material, placed in the chamber n, and by the draft of the spindle drawn through them. These ducts being formed near the lower part 95 of the bearing, the latter will be completely 100 and perfectly oiled by the upward capillary force of the spindle and bolster without any expenditure of the power which drives the spindle, while at the same time the orifices being

above the level of the oil in the chamber n and supplied as above described, will have delivered to them so limited a quantity of oil that the requirements of perfect lubrication demand nearly all that will be so furnished, and there will be but little to be carried up and discharged over the top of the bolster.

The capacity of the inducts m and m^2 , when used either together or separately, is so limited that the spindle will carry any oil which passes through them not needed for the lubrication of the step and bolster up out of the sleeve, so that the spindle will be surrounded by air from its bolster to its step in the space marked a .

Upon the outside of the case D is formed a thread, by which it is screwed into the chamber o , formed in the rail R for an oil-reservoir. From the cup e' there are carried down ducts d^2 , which terminate below the thread formed upon the case, so that oil may flow from the cup e' either through the ducts d^4 , already described, into the chamber n , or through the ducts d^2 , last described, into the oil-reservoir o . The oil, therefore, which is carried up by the capillary and rotary action of the spindle and discharged over the top of the bolster will run back either into the reservoir or into the case containing the filtering material through its appropriate ducts d^4 d^2 .

Upon the top of the case D is formed the flange d^3 , made concentric with the bolster h , and of a slightly greater circumference than the flange b upon the whirl. Upon the flange d^3 a collar, s , is fitted, which has an inwardly-projecting flange, t , upon its upper edge, which overlaps the flange b on the whirl.

When the spindle is in position and the collar passed down over it to its place and made fast upon the flange d^3 , either by a set-screw, bayonet-joint, or in any other equivalent manner, the spindle cannot be lifted from its step.

The reservoir o is made to connect with the adjacent reservoirs for adjacent spindles by means of the passage p , which is connected at a convenient place with an oil-cup, through which oil may be supplied to all the reservoirs, whether the spindles are at rest or in motion.

When the spindle is in operative position and oil has been once supplied to it, as well as to the reservoir o , and the spindle put in operation, the first effect of the rotation of the same is, by reason of its tapering form, to carry out over the top of the sleeve all the oil contained therein between the step and the bolster, after which the spindle will be in contact with the bolster and step, and not in frictional contact with the sleeve or with a column of oil between the bolster and the step; and as no oil can obtain entrance to the step at the bottom of the sleeve, and the quantity which can pass through the inducts is very small, the spindle will rotate in air between its upper and lower bearing-points—a result not heretofore obtained in any reservoir oiling spindle having its step and bolster connected.

As air is a much thinner fluid than oil, it is

manifest that a great saving in power is made by bringing it in contact with the spindle instead of oil upon that part of it, and as the oil is supplied near the point x through the induct m^2 , which is covered by the fibrous material in the chamber n outside the rotation of the spindle, and in such quantity that little or none from the inflow at this duct is ordinarily carried up and discharged over the top of the bolster, it is manifest that much less power is required to drive the spindle than when the oil must be elevated to the bolster and is continually passing over its top, only to run down and again make the circuit. It is also evident from the arrangement of parts as shown that no oil can be wasted by being thrown off the spindle, and that it is difficult, if not entirely impossible, for dust or dirt to come in contact with the oil in use.

The duct m being arranged to discharge its oil into the space in the sleeve between the bolster and step, the oil will not come in contact with the spindle until, after flowing down the interior of the sleeve, it comes in contact with the spindle at the step, and the amount supplied to the step will be so little in excess of the actual requirements for lubrication that there will be but little to be carried upward by the rotary action of the spindle. The spindle, therefore, will be perfectly oiled without being in frictional contact with either metal or oil between the step and the bolster, and will not be compelled to sustain a column of oil reaching from its lower to its upper bearing to lubricate the latter, while the oil which overflows the bolster is free to return again to the bearing-surfaces without coming in contact with the air in the mill-room. It will also be observed that I have provided a method of keeping the spindle in place which is at once neat and perfect, while the part used to accomplish this purpose is entirely below the band, and, besides, being thus out of the way of the band, serves as an additional protection from dirt to the oil-cup of the spindle-case. It will also be observed that by this construction I am enabled to make my spindle smaller and lighter below its bolster-bearing without impairing its lubrication or strength, and that by so lightening it I am enabled to produce a spindle which will require less power when in operation.

What I claim as new and of my invention is—

1. The spindle A and reservoir o , in combination with the sleeve H , provided with the step and bolster, the air-space a , and induct m , and the case D , having the lip e , and inducts d^2 and d^4 , through the former of which the oil discharged over the top of the bolster is returned to the reservoir, and through the latter of which the oil is supplied from the reservoir to the spindle, substantially as described.

2. The combination, with the case D , having the oil-chamber n , of the sleeve H , extending into said case, and provided with the bol-

ster, step, and oil-duct, and the spindle A, adapted to revolve within the sleeve without frictional contact with either oil or metal between the bolster and step bearings, substantially as described.

5. In combination, the spindle A, the sleeve H, comprising the bolster *h* and the step *l*, the case D, having chamber *n*, and the packing *r*, the sleeve being provided with the induct *m*, placed near the top of the chamber *n*, which contains the packing *r*, substantially as described.

10. In combination, the oil-reservoir, the case D, and sleeve H, comprising the bolster *h* and the step *l*, with the porous packing *r*, the packing surrounding the step, sleeve, and bolster, and the whole inclosed in the case and con-

tained in the oil-reservoir, substantially as described.

15. In combination with the case D, provided with the flange *d*³ and spindle A, the whirl B, provided with the flange *b*, and the collar *s*, provided with the inwardly-extending flange *t*, substantially as described.

20. In combination with the spindle A and case D, provided with the lip *e*, the whirl B, having a lip extending downward within the lip *e*, and the lip *c*, extending downward outside of the lip *e*, and the collar *s*, surrounding the lip *e*, substantially as described.
